UNITED STATES PATENT OFFICE.

CHARLES E. SPAID, OF SIOUX FALLS, SOUTH DAKOTA.

AUTOMOBILE-RADIATOR ATTACHMENT.

1,418,334.

Specification of Letters Patent. Patented June 6, 1922.

Application filed March 23, 1917. Serial No. 156,998.

To all whom it may concern:

Be it known that I, CHARLES E. SPAID, a citizen of the United States, residing at Sioux Falls; in the county of Minnehaha and State of South Dakota, have invented certain new and useful Improvements in an Automobile-Radiator Attachment, of which the following is a specification.

This invention relates to an improvement 10 in a radiator attachment which is adapted to be fitted and held in place over the open front of an automobile radiator, and which may be provided with a heater to supply heat to the radiator to warm the water in 15 the radiator coils and prevent freezing of the same, and at the same time to warm the engine to permit more ready starting of the same.

An object of this invention is to provide 20 such a device as is set forth above which may be readily attached and detached without the use of special tools of any sort, and which is so constructed that the full volume of air heated by the generating means will 25 pass through the radiator and around the engine, thus making the device very economical in use.

A further object lies in the construction 30 of the device in such a manner that fresh air at atmospheric temperature can be supplied to circulate through the radiator.

With the above and other objects in view, my invention consists in certain novel features of construction and combinations of 35 parts which will be hereinafter set forth in connection with the drawings and then more particularly pointed out in the claim.

In the drawings:

Figure 1 is a view in perspective of the 40 invention illustrating the radiator and other parts of the automobile contingent thereto by means of dotted lines.

Figure 2 is a view in front elevation.

Figure 3 is a vertical sectional view.

The main case 1 of the device is made to have an outer contour corresponding approximately to the outline of a front elevation of the particular radiator to which the device is to be fitted, and in this connection it will be understood that the device will be particularly constructed for use with various makes of automobile having variously designed radiators.

From the bottom 2, the rear wall 3 of the 55 case 1 is intended to be perfectly straight, or

to be shaped to fit closely adjacent to the forward end of the radiator to which the device is to be fitted, and the outer wall 4 adjacent the bottom 2, which is perhaps spaced a distance of three inches from the rear wall 3, is sloped gradually inwardly and then upwardly from this bottom 2, and when the space between the forward and rear walls is reduced to approximately three-fourths of an inch, the outer wall 4 is then 65 extended upwardly parallel with the rear wall 3. Side and top walls 5 and 6 are connected between the forward and rear walls 4 and 3 and in the lower part of the casing thus formed, a partition 7 is disposed 70 in horizontal arrangement so that a fuel chamber 8 is provided in the lower part of the casing 1, a spout or filling tube 9 being preferably extended from one side of the casing to permit the supply of oil to the 75 chamber 8.

The rear wall 3 is provided with the openings 10 which are formed through substantially the entire area thereof so that air may readily pass into and from the interior of 80 the casing above the partition 7, through these openings 10. Burners 11 are mounted in the partition 7 having wicks 12 which extend down into the fuel chamber 8 and the openings 13 are provided to permit access 85 to be had to these burners 11 and are provided with the doors 14 to close the same it being preferable that these doors 14 be provided with a glass, mica, or other transparent window so that the burners may be 90 viewed therethrough. It is perhaps preferable that a pair of burners be located adjacent each side of the casing so that the heat within the casing will be more evenly distributed, and under ordinary working 95 conditions the air flowing through the lowermost of the openings 10 will supply sufficient oxygen to support combustion at the burners and the heated air from the burners will pass out through the upper and intermediately arranged openings 10, thus creating a natural circulation of cooler air into the casing lower down therein and as this air is heated and rises, it will be discharged adjacent the top of the casing, and 100 from the middle portion thereof.

As has been stated, the casing is shaped to have a contour corresponding to the outline of the particular radiator to which it is to be fitted and upon which it is to be used, and a 110

packing strip 15, which may be of asbestos or other suitable material is arranged upon the face of the inner wall 3 around the edge thereof to bear against the face of the radiator and to establish a tight joint, the hook-shaped member 16 being carried by the casing 1 to be caught around the neck upstanding from the filler opening for the radiator, and hooks 17 being mounted on the sides 5 of the casing near the lower end thereof to be engaged over pins, studs, or other suitable projections mounted on the radiator casing, and these hooks holding the casing in a position where the packing material 10 15 15 is compressed between the rear wall and the face of the radiator casing.

Where the device is mounted as is above set forth, the natural circulation of the air from the engine hood through the radiator 20 and through the lowermost openings 10 to be heated within the casing and to be again discharged into the hood through the radiator from the upper openings 10 will normally supply the proper amount of air to 25 the burners and create the necessary draft for the flames at the burners. However, if sufficient air is not supplied to the burners in this way, then the doors 14 may be slightly opened and in this way an increased 30 supply of air will be received from the atmosphere. Also it is preferable that a vent opening 18 be provided through the front wall 4 of the casing near the top thereof to be closed by the cover 19, and further 35 this expedient might be resorted to when too great a supply of heated air is passing from the casing through the radiator. However it is perhaps desirable that some means be provided to supply air to the radiator and 40 after passing therethrough, to the engine hood and to accomplish this purpose, I pass the tubes 20 through the forward and rear walls 4 and 3 so that the inner ends thereof open through the central portion of the inner wall 3, and caps 21 are provided to be 45 fitted over the outer ends of these air supply tubes 20 to close the same normally. By removing the caps 21, air will pass directly from the atmosphere through the 50 tubes 20 and around the coils of the radiator from whence it will pass to the engine hood. To determine the temperature of the air within the casing 1, a thermometer 22 is mounted within an opening formed in the 55 forward wall 4 where it will be visible, and by the regulation of the parts as above set forth, any desired temperature of the air passing through the openings 10 can be attained. It is preferable that the casing 1 be 60 shaped so that the forward and rear walls 4 and 3 are notched at the approximate centers of the lower edges and the bottom 2 is made to follow this configuration, thus providing a notched out opening 23 in which 65 the starting crank will fit, provided the en-

gine is not fitted with some sort of an attachment for starting.

In the use of the device, adaptations may be made to have the device fitted in place only while the machine is standing upon the 70 street or in a garage to prevent freezing of the cooling water. Or the device might be fitted in place to be used just previous to starting the engine so that the water in the radiator would be warmed up and also the 75 engine structure would be warmed to permit more ready starting thereof. Or this device might even be fitted in place to remain stationarily mounted during the use of the automobile, where the machine is used in very 80 cold weather and where the passage of atmospheric air over the coils of the radiator would cool the water to such an extent that the engine cylinders will be cooled and will in consequence not operate properly and 85 with the greatest efficiency. It will of course be understood that when the device is fitted in place and the machine is operated, it will be possible to remove the caps 21 in order that atmospheric air can pass through the 90 tubes 20 to augment the air supplied through the openings 10, this adjustment of the parts however, being dependent upon the indications of the thermometer and the temperature which it is desired to maintain. 95

While I have herein shown and described only one specific form of the invention, it will be understood that heating means other than the oil burners as here illustrated might be used, that some other form of 100 fastening means can be supplied, and that other modifications and variations might be made in the form and arrangement of the parts without departing from the spirit and scope of this invention, and hence I do not 105 wish to be limited except to such points as may be set forth in the claim.

I claim:

A radiator attachment comprising a casing shaped to conform to the outline of a 110 radiator, means for detachably securing said casing to the front of a radiator, said casing provided with spaced front and rear walls, said rear walls provided with a plurality of discharge apertures formed therein, a plurality of fresh air supply tubes extending through said front and rear walls and provided with their discharge ends communicating with the front of a radiator upon which said attachment is adapted to be 115 placed, and caps threaded upon the outer end of said tubes for permitting the outer ends of said tubes to be positively closed when it is so desired.

In testimony whereof, I affix my signature 120 in the presence of two witnesses.

CHARLES E. SPAID.
